(57) **CLAIM**

The ornamental design for a wedger pusher, as shown and described.

DESCRIPTION

FIG. 1 is a perspective view an embodiment of a wedger pusher;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a back view thereof.

The broken lines showing of various portions and other elements in the Figures are for the purpose of illustrating unclaimed portions and form no part of the claimed design.

1 Claim, 4 Drawing Sheets(56)
